Primary Examiner — Steven J Czyz

(57) **CLAIM**

The ornamental design for a handbag as shown and described.

DESCRIPTION

1.1 : Perspective

1.2 : Right

1.3 : Back

1.4 : Top

1.5 : Bottom

The evenly spaced broken lines depict stitching and form part of the claimed design. The long-short broken lines depict boundaries of the claimed subject matter and form no part of the claimed design.

Figure 1.1 is a perspective view of the bag; Figure 1.2 is a side view of the bag; Figure 1.3 is a back view of the bag; Figure 1.4 is a top view of the bag; Figure 1.5 is a bottom view of the bag.
